TOY BOAT

Victor Goldberg and Max L. Goldberg,
Baltimore, Md.

Application January 9, 1934, Serial No. 705,961

21 Claims.

(Cl. 46—93)

This invention relates to toy boats formed from an initially flat blank of paper and inserts to be associated therewith all of the character as set forth in our Patent No. 1,943,474, dated 5 January 16, 1934, and of which this application is a continuation in part.

In addition to the objects set forth in the above referred to application other objects of this invention are to provide flaps on the hull of the 10 boat for locking the inserts therein, and for forming said flaps integral with the blank from which said hull is formed, said flaps furthermore when fastened in position defining the decks of said hull.

15 The paper boat described hereinbelow and the method of forming the same is clearly shown in the accompanying drawings, in which:—

Fig. 1 is a side elevational view of the complete boat showing the hull and attached insert.

20 Fig. 2 is a front elevational view of the boat.

Fig. 3 is a plan view of the boat.

Fig. 4 is an elevational view of an insert.

Fig. 5 is a cross-sectional view of the hull taken on line 5—5, Fig. 3, looking in the direction of the 25 arrows.

Figs. 6 and 7 are top and bottom views of one form of blank.

Figs. 8 to 22 inclusive show in succession the steps of folding the hull of the boat from the 30 blank.

Fig. 23 shows a mounting for the boat.

Figs. 24 and 25 illustrate top and bottom views of a modified form of blank.

Figs. 26, 27, 28 and 29 show in succession the 35 steps of folding the hull of the boat from the modified form of blank.

Referring to the complete showing of the boat in Fig. 1, A designates the hull of the boat which comprises fore and aft decks *a* and *b* spaced 40 apart as shown, each of the decks being square shaped and arranged so that a diagonal of each coincides with the longitudinal axis of the boat. Laterally inclined sides *d* are connected to the corners *c* of the decks *a*, *b* which converge to a 45 keel *e*. Beneath each of the decks *a*, *b* are parallel spaced vertical walls *f*—*f*, *g*—*g* which are in planes parallel with the vertical plane along the longitudinal axis of the boat and support said decks, connecting the same with the keel *e*, the 50 outer edges of said walls being inclined from the outermost corners of the decks *a*, *b* to the ends of the keel, as clearly shown in Fig. 1.

On each side of the vertical sides *f*—*f*, *g*—*g* and connecting the same with the laterally inclined sides *d* and keel *e* are transverse sub-

stantially vertical walls or sides *h*. Projecting from the medial horizontal center of the inclined sides *d* are downwardly extending fins or flaps *i* which function to maintain the hull A on an even keel when said hull is either floating or to maintain the hull in an upright position when the same is placed on a flat surface as for example a table top. The bottom edges *j* of each of the fins or flaps *i* are straight and are of substantially the same length and always parallel to the keel *e*, 10 irrespective of the angular position of the fins or flaps *i*. It is thus apparent from an inspection of Fig. 2 that the fins or flaps *i* to all intents and purposes serve as buttresses to hold the hull of the boat upright.

15 Located between the decks *a* and *b* is an open hatch *m*, the side walls *n* of which are connected to the laterally inclined sides *d* and the end walls *p* of which are connected to the inner portions or ends of the walls *h* and vertical walls *f*—*f*, *g*—*g* 20 as clearly shown in Figs. 3 and 5. It will be observed from an inspection of Fig. 5 that the hatch *m* extends clear to the bottom of the keel *e* of the hull and is divided at the end walls *p* by the space *s* formed by the parallel vertical walls *f*—*f*, 25 *g*—*g* and it being understood that the opposite end walls *p* of the hatch are similarly divided. The purpose of this space *s* will be hereinafter described.

As heretofore stated the decks *a*, *b* are square and arranged with the diagonals in the same 30 plane as the longitudinal axis of the boat. The decks *a*, *b* each present smooth uninterrupted surfaces from edge to edge and corner to corner as most clearly shown in Fig. 3 and are positively secured to the hull proper thus preventing 35 spreading apart of the vertical walls *f*—*f* and *g*—*g* and at the same time increasing the rigidity of the structure as a whole. An additional function of the decks *a*, *b* and the manner in which the same are fastened down will be described hereinafter.

40 At this point attention is directed to the fact that the above defined portions of the hull A are all integral and are formed from a single unitary flat blank by a folding process in the manner to be hereinafter set forth.

45 Adapted to be associated with the hull A is an insert B provided with a lower portion *w* and an upper portion *u* having the characteristics of the superstructure of a boat. This insert B is preferably formed flat and of a substantially rigid material as for example cardboard, and of a thickness equal to the space *s* between the vertical walls *f*—*f*, *g*—*g*. The lower portion *w* of the insert B is so formed as to possess the outline of the hull on 50 55

the vertical longitudinal axis thereof so as to snugly fit in the spaces *s* of the hull. When so positioned in the hull the portion *w* will rest on the bottom of the keel *e* and engage the junction 5 of the vertical walls *f-f* and *g-g*. Referring to Figs. 21 and 22 it will be noted that the portions of the hull constituting the decks *a, b* are so arranged prior to their being fastened down in the manner to be hereinafter described, 10 as to permit the ready insertion of the lower portion *w* of the insert *B* into the spaces *s*. In order that the decks *a, b* present a smooth uninterrupted surface, the upper portion *u* of the insert *B* having the characteristics of the super- 15 structure of a boat is arranged to project from the central part of the underportion *w*, see Fig. 4, so as to clear the surfaces of either of said decks as clearly shown in Fig. 1.

While only a single flat insert *B* has been shown 20 in conjunction with the hull *A* it is to be understood that said hull is adapted to receive a plurality of inserts arranged in intersecting planes interconnected in the manner clearly shown and described in our Patent No. 1,943,474 above referred to. It is to be further understood that the inserts may be made to depict the super- 25 structure of any type of vessel.

As heretofore pointed out the above described hull is formed from an initially flat blank. Such 30 a blank is shown in Figs. 6, 7, 24 and 25 and comprises a blank of paper or any other suitable material, rendered moisture proof if desired, of comparatively strong texture and stiffness, yet capable of being readily folded.

35 Figs. 6 and 7 show respectively top and bottom views of the blank which has ruled or printed on each side thereof a plurality of directional fold lines, each bearing a definite relation to the other and each of a predetermined length, the lines 40 on one side of the blank being also definitely located with respect to the lines on the other side of the blank. These lines indicate where and in what sequence the necessary folds are to be made to form the hull in the manner now hereinafter 45 set forth. As will be noted the blank is provided along the opposite edges thereof with integral extending marginal portions or flaps *10, 11, 12* and *13* the purpose of which will be hereinafter described.

50 Starting with the blank, having the top side, Fig. 6, facing upwardly, folds are made along the lines *1-1* bringing the flaps *10-11* together as shown in Fig. 8, it being immaterial whether the flap *10* is above or below the flap *11*. The blank 55 is then folded along the lines *2-2* assuming the form shown in Fig. 9, the flaps *12-13* being each then folded backwardly and underneath the blank which is then folded along the lines *3-3* to take the form shown in Fig. 10. Reversing the 60 blank, Fig. 11, a fold is made along the line *4*, the blank then taking the form of Fig. 12 which shows one end face thereof in elevation. Opening each end face of the blank as shown in Fig. 13, each corner *15, 16, 17, 18* is pulled out and 65 folded on the lines *5* the blank then assuming the form illustrated in Fig. 14. Each end corner *15, 16, 17, 18* is then bent completely back, corners *15-16* being placed beneath the flap *12* and corners *17-18* similarly placed beneath the flap *13*.

70 The blank at the completion of this operation will take the form shown in Fig. 15 and upon opening the same by pulling or separating the end portions covered by the flaps *12-13* will take the form of a box as illustrated in Fig. 16. The 75 top and bottom edges of each of the sides *19-20*

of the box are then brought together by folding along the horizontal line *6*, the blank then taking the shape shown in Fig. 17. Each end portion covered by the flaps *12-13* are bent inwardly in the directions of the arrows (Fig. 17) on the lines 5 *7-7* which are on the bottom of the blank and which upon the completion of the folding on lines *7-7* will take the form shown in Fig. 18. The blank is then folded on line *8-8* which then takes the shape of Fig. 19. By holding the blank somewhat tightly at the flaps *10-11* and pulling the corners *21-22* outwardly and upwardly in the direction of the arrows (Fig. 19), the blank will then take the form of the hull, Fig. 20, and by pulling the flaps *12-13* outwardly, the form of 10 the hull *A*, Fig. 21.

The hull *A*, in this form is adapted to receive the insert *B* in the spaces *s-s* as shown in Fig. 22. The flaps *12-13* are then adapted to be separated on the tear-line *9-9* which for convenience 20 may be perforated or scored to facilitate ready tearing along the same. Each flap *12-13* is thus divided into two separate flaps *12^a-12^b, 13^a-13^b* which are provided along the outer ends thereof with adhesive surfaces *25*, which function to 25 fasten said flaps to the hull and to each other in overlapping engagement to form respectively the decks *a-b*. These divided flaps on each end of the hull are bent inwardly, first one *12^a* being fastened to the hull and then the other associated flap *12^b* which is likewise bent inwardly (in the direction of the arrows, Fig. 22) and similarly fastened down, to the first mentioned flap *12^a*, said flaps thus locking the insert *B* to the hull 30 without being in any manner positively associated 35 with said insert. The flap *13* in Fig. 22 is shown fastened down to the hull *A* to form the deck *a*. It will be noted that the divided flaps are each of the same configuration and when folded over completely cover the spaced portions *26-27* of 40 the hull as shown by the flaps *13* forming the deck *a*.

Fig. 23 illustrates one manner of mounting the boat on a support. Each of the fins or flaps *10-11* are provided along the outer edge portion 45 of one side with adhesive zones or surfaces *30* shown on the blank Fig. 6. These adhesive portions *30* of the flaps *10-11* are adapted to be bent outwardly and fastened to a flat support *31*, thus rigidly mounting the boat to said support. It is 50 obvious that the support *31* may assume various shapes and the portions *30* appropriately bent for attachment thereto.

The hull *A* of the boat may also be formed from a blank such as shown in Figs. 24 and 25 which 55 has the same form as the blank previously described and shown in Figs. 6 and 7, differing therefrom only in the specific fold line arrangement.

The folding of the blank is started by first 60 folding on the lines *1-1* bringing the flaps *10* and *11* together in superposed relation as shown in Fig. 26. In this form the blank is then creased along the lines *2, 3*, and at the same time the flaps *12, 13* are bent backwardly to engage the 65 bottom side of the blank as shown in Fig. 27. Each corner of the blank is then creased along the lines *4* bringing adjacent portions of the blank into contact in the manner clearly shown in Fig. 28, to form the triangular corners *35, 36, 37* and *38*, the blank thus taking the form illustrated in Fig. 29.

At this stage of the folding each of the corners 70 *35, 36, 37* and *38* are folded inwardly in the manner indicated by the arrows, see Fig. 29, and 75

placed beneath the flaps 12, 13, the blank then assuming the box-like form shown in Fig. 16. From this box form (Fig. 16) on, the blank is folded along the remaining characterized lines 5, 6 thereon, in the same manner as indicated in Figs. 17 to 21 inclusive and as described hereabove, to form the hull A.

An inspection of the blanks shown in Figs. 6, 7 and 24, 25 will show that both blanks have identical configurations and by virtue of the different fold line arrangement inscribed thereon, said blanks are accordingly differently folded to produce identical hulls A.

The blank of Figs. 24 and 25 is provided in the same manner as the blank of Figs. 6 and 7 with adhesive surfaces 25 on the flaps 12 and 13, and adhesive surfaces 30 on the flaps 10 and 11, the flaps 12 and 13 being also provided with tear-lines 7, all having the same functions as described 20 above with reference to the blank of Figs. 6 and 7.

If desired the blanks of Figs. 6, 7 and 24, 25 may have additionally provided thereon adhesive surfaces 40 see Fig. 25. These surfaces 40 are triangular in form and in the final form of the hull A constitute the inner or opposing sides of the vertical walls f-f and g-g. In view of the fact that in some cases it may be desirable to employ the hull without the insert B, the adhesive surfaces 40 may function to unite 25 the opposed vertical walls f-f and g-g together, thus reinforcing the prow and the stern of the hull defined by said vertical walls and in conjunction with the divided flaps 12a-12b, 13a-13b producing a rigid hull incapable of unfolding or 30 falling apart as a result of constant usage. In the event that the insert B is used with the hull A in the manner as described hereabove, the adhesive surfaces 40 may function to permanently fasten the vertical walls f-f, and g-g, thereto, 35 independent of the locking of said insert B between said walls by the divided flaps 12a-12b and 13a-13b. It is to be understood that the use of the adhesive surfaces 40 on the two forms of blanks is entirely optional, said surfaces 40 40 being shown on the blank of Figs. 24 and 25 merely by way of an example.

It is further pointed out that the divided flaps 12a-12b and 13a-13b are in themselves sufficient when fastened down to the hull to form the decks 50 a and b, to render the hull incapable of unfolding itself or falling apart with constant use, and that the hull in this form is adaptable for use without the insert B.

We claim:

55 1. A toy boat comprising a hull formed as an integral unit from an initially flat blank of material, oppositely disposed flaps projecting from the hull and adapted to be horizontally fastened in overlapping engagement to each other and to said hull and defining a deck thereof.

60 2. A toy boat comprising a hull, means within said hull adapted to receive a separable insert having the characteristics of the superstructure of a boat, and means forming part of said hull superposed over a portion of said insert for locking said insert in said first mentioned means.

65 3. A toy boat comprising a hull, means integral with said hull adapted to receive an insert having the characteristics of the superstructure 70 of a boat, and flaps on said hull and independent of any positive association with said insert for locking said insert to said hull.

75 4. In a toy boat, a hull formed as an integral unit from an initially flat blank of foldable material, a detachable insert having the character-

istics of the superstructure of a boat provided with an underportion, means within said hull adapted to intimately receive said underportion, and additional means on said hull superposed over said underportion for locking said insert in 5 said first mentioned means.

5 5. In a toy boat, a hull formed as an integral unit from an initially flat blank, an insert having the characteristics of the superstructure of a boat, means on said hull adapted to intimately 10 receive said insert, adhesive zones formed on said hull for fastening spaced portions of said hull together and for locking said insert in place.

10 6. In a toy boat, a hull, an insert having the characteristics of the superstructure of a boat, laterally spaced portions forming part of said hull and adapted to intimately receive said insert, and means carried by said hull for fastening said portions against separation and for locking said 15 insert in position.

15 7. As an article of manufacture, a blank from which a toy boat is formed by a series of folding operations, and means wholly within the boundaries of said blank and unitarily associated therewith for securing spaced portions of the boat together upon completion of the folding of said 20 blank.

25 8. As an article of manufacture, a blank from which a toy boat is formed by a series of folding operations, marginal reinforcing flaps shaped to form the deck of said boat extending from opposite edges of said blank, each of said flaps having more than two side edges.

30 9. As an article of manufacture, a blank from which a toy boat is formed by a series of folding operations, said blank being of such form as to have a greater length than width and symmetrical along the major and minor axis thereof, marginal reinforcing flaps extending from opposite edges of said blank, and marginal oppositely disposed supporting flaps extending from other edges of said blank, each of said flaps having more than 35 two side edges.

40 10. As an article of manufacture, a blank of greater length than width from which a toy boat is formed by a series of folding steps comprising a flat sheet of foldable material symmetrical in form about the major and minor axis thereof, marginal reinforcing portions extending from opposite side edges of said blank each being identical 45 in form, a tear line dividing each marginal portion, and fastening means on said marginal portions.

50 11. In a toy boat, a hull comprising a deck and a hatch, an insert having the characteristics 55 of the superstructure of a boat mounted within said hatch and means on said insert extending beneath said deck and cooperating therewith to lock said insert to said hull.

60 12. In a toy boat, a hull, a separable insert having the characteristics of the superstructure of a boat provided with an underportion fitted to said hull, means constituting portions of said hull disposed across portions of said insert for locking said insert in position.

65 13. In a toy boat, a hull, an insert having an upper portion defining the superstructure of a boat and a lower portion fitted to said hull, oppositely disposed means associated with said hull and disposed across a portion of said insert, said 70 means being positively connected to said hull to lock said insert in position.

75 14. In a toy boat a hull formed as an integral unit from an initially flat blank of foldable material, said hull at one stage of the folding defin-

- ing a longitudinal channel at each end thereof, oppositely disposed, flaps projecting from said hull, an insert having the characteristics of the superstructure of a boat seated in said channels, 5 said flaps adapted to be horizontally fastened to said hull to form the decks thereof, said flaps bridging said channels to lock said insert therein and restraining the portions of said hull on each side of said insert against lateral separation.
- 10 15. A boat comprising a deck, a hatch adjacent said deck, a recess beneath said deck communicating with said hatch, said recess being defined by vertical walls spaced a distance apart less than the width of said hatch, an insert having 15 the characteristics of the superstructure of a boat seated in said hatch, means on said insert extending within said recess in engagement with the walls thereof, said deck bridging the space between said walls and restraining outward movement of said insert relative to said hull.
16. In a toy boat, a hull formed as an integral unit from an initially flat blank of foldable material, said hull at one stage of the folding defining a longitudinal channel at each end thereof, 25 oppositely disposed flaps projecting from said hull to form the decks thereof, said flaps bridging said channels and restraining the portions of said hull on each side of said channels against lateral separation.
- 30 17. An insert for use with the hull of a toy boat comprising an upper portion having the characteristics of the superstructure of a boat and a lower portion adapted to be fitted to said hull, said upper and lower portions being separated for a portion of the length of said insert from at least one side thereof to a point substantially near the center of said insert.
18. In a toy boat, a hull, securing means laterally extending from the sides of said hull and connected to a supporting structure for locking the hull thereto. 5
19. A preformed imperforate blank of water proof paper adapted to be folded to form a toy boat, said blank being provided with designated fold lines on opposite sides thereof adapted to be folded in the order of their designation and each to the limit of their extent, the portions of 10 the blank defining the deck of the toy boat being arranged at opposite sides of said blank and so shaped with reference to the blank proper as to constitute the last portion of the blank to be folded in forming said toy boat. 15
20. An insert for use with the hull of a toy boat comprising an upper portion having the characteristics of the superstructure of a boat and a lower portion adapted to be fitted to said hull, said upper and lower portions being separated in part to define at least one opening whereby to permit of the insertion of a locking medium therethrough. 20
21. The method of assembling a toy boat from an initially prepared blank designed to form the 25 hull of the boat, and an insert having the characteristics of the superstructure of a boat; comprising the steps of folding the blank along designated fold lines provided thereon to a stage of the folding that defines a channel in the hull, 30 placing the insert within said channel, folding the remaining portion of the blank over a pre-determined portion of said insert, and then fastening said remaining blank portion in place to lock said insert to said hull. 35

VICTOR GOLDBERG.
MAX L. GOLDBERG.
